(57) **CLAIM**

The ornamental design for a wearable sensor, as shown and described.

DESCRIPTION

FIG. 1 is a front perspective view of a wearable sensor showing the new design;

FIG. 2 is a top plan view thereof;

FIG. 3 is a bottom plan view thereof;

FIG. 4 is a right side view thereof;

FIG. 5 is a left side view thereof;

FIG. 6 is a rear view thereof;

FIG. 7 is a front view thereof;

FIG. 8 is a front perspective view of another wearable sensor showing the new design;

FIG. 9 is a top plan view thereof;

FIG. 10 is a bottom plan view thereof;

FIG. 11 is a right side view thereof;

FIG. 12 is a left side view thereof;

FIG. 13 is a rear view thereof; and,

FIG. 14 is a front view thereof.

The broken lines are for the purpose of illustrating portions of the article and form no part of the claimed design.
